INVENTOR
THOMAS AHEARN

BY *Fetherstonhaugh Co. Inc.*

Patented Sept. 12, 1922.

UNITED STATES PATENT OFFICE.

THOMAS AHEARN, OF OTTAWA, ONTARIO, CANADA.

PHONOGRAPH-NEEDLE BUFFER.

Application filed July 30, 1920. Serial No. 400,134.

To all whom it may concern:

Be it known that I, THOMAS AHEARN, a subject of the King of Great Britain, and resident of the city of Ottawa, in the Province of Ontario and Dominion of Canada, electrical engineer, have invented certain new and useful Improvements in Phonograph-Needle Buffers, of which the following is a specification.

10 This invention relates to improvements in buffers for needles of sound reproducing machines, and in which the needle is lowered by mechanical or manual means on to the record, and the objects of the invention are 15 to enable the needle to be gradually lowered in place of being dropped quickly on to the record thereby avoiding the production of scratches, holes or other undesirable damage to the record, and it consists essentially of a 20 pivoted buffering member preferably carried by the sound box and adapted to engage the surface of the record in advance of the needle and to cause the same to be lowered on to the same, and without damage to the 25 disc, all as hereinafter more fully set forth and described in the accompanying specifications and drawings.

In the drawings:—

Figure 1 is a perspective view shewing the 30 sound box, needle and record and my invention applied thereto.

Figure 2 is a side view shewing the buffer and needle in playing position.

Figure 3 is the same view shewing the 35 buffer engaged with the record before the needle comes into playing position.

Figure 4 is a sectional view through the buffer.

In the drawings, like characters of reference indicate corresponding parts in all 40 figures.

Referring to the drawings:—

A indicates the tone arm, B the sound box, C the needle and D the record of a 45 sound reproducing machine of any convenient type of construction.

E represents my buffering element pivotally supported from the sound box and adapted to hang by gravity in a substantially vertical 50 position, having a resilient contact member 10 on the lower side.

In order to provide for adjustment, this contact member is conveniently mounted in a sleeve 10^a having a threaded surface en-

gaged with correspondingly threaded recess 55 11 in the body portion 12 of the buffering element.

It will be seen that when the sound box is raised, the position of the buffering element will be substantially vertical as indicated in 60 Figure 3. As the sound box is lowered, the resilient tip 10 on the buffering element will first engage the record D.

Assuming that the record has been already 65 started and is moving, the movement of the record will swing the lower part of the buffering element forward as indicated in Figure 2 permitting the needle to come into free playing contact with the record.

Owing to the fact that the buffering element 70 during this movement, supports the weight of the sound box and partly of the tone arm, the movement will be sufficient to gradually lower the needle without the rapid drop, such as attends the operation of starting a 75 talking machine and which would mar the surface of the record.

As many changes could be made in the above construction and many widely different embodiments of my invention within 80 the scope of the claims, constructed without departing from the spirit or scope thereof, it is intended that all matter contained in the accompanying specification and drawings shall be interpreted as illustrative and 85 not in a limiting sense.

What I claim as my invention is:—

1. In a sound reproducing machine, a sound member, a buffering member pivoted to the sound box, and a resilient contact member 90 adjustably supported from the buffering member.

2. In a sound reproducing machine, a pivoted buffering member having a threaded socket therein, and a resilient contact tip adjustably held in the socket.

3. In a sound box, a pivoted buffering member comprising an arm pivoted to the side of the sound box and a sleeve integral with the arm and extending laterally therefrom beneath the sound box, and a resilient contact member adjustably held in the sleeve.

In witness whereof I have hereunto set my hand in the presence of two witnesses.

THOMAS AHEARN.

Witnesses:
